CLARENCE E. BEACH, OF BINGHAMTON, NEW YORK, ASSIGNOR TO GEORGE C. KNAPP,
OF NEW YORK, N. Y.

SIGNALING SYSTEM.

1,117,633.

Specification of Letters Patent. Patented Nov. 17, 1914.

Application filed December 24, 1913. Serial No. 803,572.

To all whom it may concern:

Be it known that I, CLARENCE E. BEACH, a citizen of the United States, residing at Binghamton, in the county of Broome and State of New York, have invented certain new and useful Improvements in Signaling Systems, of which the following is a specification.

My invention relates to signaling systems and particularly to alarm systems for protecting localized territory and for protecting buildings, such, for example, as factory buildings and factory premises. Systems of this kind are designed to provide means for sending an alarm, such as an alarm of fire, from any of a number of stations and to give warning signals at various points in a building or premises to warn the occupants to escape therefrom.

One object of my invention is to so connect the different signal stations that if two or more are operated at the same time, such operated stations will take control of the system through their non-interference magnets in a predetermined order, as for example, the lower of the operated stations first, and then, if more than two were operated, the others in corresponding order, thus warning those above the fire that their escape is likely to be cut off and haste is therefore necessary, while reassuring those below the fire that they may safely give the right of way to persons from the upper floors.

Another object of my invention is to so connect the different signal stations that if a signal is already being transmitted from a station on an upper floor and a station on a lower floor is operated, the upper station will, for like reason, stop at the end of its current round, letting the lower station transmit its signal without delay.

Another object of my invention is to provide such mechanism in the signal boxes that if two or more are operated at or about the same time, the signals from all of them will be transmitted in a predetermined order, without interference one with another.

Another object of my invention is to make possible the use of a series of electromagnetically operated signal devices requiring a powerful electric current, such as single stroke direct acting bells, shunting bells, motor- or magnet-driven horns, etc., controlled from a plurality of signaling sta-

tions in a simple manner (without the employment of relays and local batteries) while keeping every part of the system under constant test by means of a very weak current in the reverse direction.

In United States Patent No. 1,082,831 issued to me under date of May 20, 1913, is shown a method of signaling from a single station, by reversing the current in the signal responsive part of the circuit while allowing the current in the rest of the circuit to flow in the normal direction. The present invention is an improvement over that described in the above patent in its adaptation to the use of a plurality of non-interfering successive signaling stations.

My present invention is particularly designed for utilizing inexpensive signaling boxes at the various stations, as, for example, those known in the art as sector boxes, which may be wound during the operation of pulling and which are capable of running for a limited number of rounds only after such pulling.

The arrangement and operation of my improved system will be clearly understood by reference to the accompanying drawing in which—

Figure 1 is a diagram of the circuit of a typical system and Fig. 2 shows the signaling mechanism of one of the stations.

Like characters refer to like parts throughout.

Referring to Fig. 1, the system is shown as comprising three stations A, B and C arranged in a vertical series. At each of these stations, a signal receiving device may be installed, this device being shown as a single stroke bell 1 at station C and being represented at the other stations by suitable devices 2. At one end of the series of stations I provide the current source 3 and at the opposite end, electrically, I provide two suitable resistances 4 and 5. These resistances are shown as magnets adapted to control the connection of a suitable alarm device 6 with its battery 7. The signaling mechanism installed at each of the stations is shown diagrammatically in Fig. 2.

As shown in Fig. 2, the sector operated driving train for the signal wheel is adapted to be wound each time the box is pulled, and when released rotates the signal wheel a predetermined number of times.

The pull lever 8 is connected with the 110

sector gear 9 and the spring 10 is provided to be wound when the sector is swung downwardly and to restore the sector when released. The details of the driving train 5 are not shown, as any well known mechanism may be used having interposed ratchet connecting the sector gear and the signal wheel 11, to transmit motion to the signal wheel only during the movement of the sector in one direction. Associated with the signal wheel is the signaling lever 12 having a projection coöoperating with the teeth of the signal wheel 11. This lever has the insulating stud 13 for actuating the contact springs 14 and 16 which are connected together by a bar of insulating material. These springs coöperate respectively with contact springs 15 and 17. Secured to a gear on the signal wheel shaft is a pin 18. 10 The prop lever 19 has an insulating stud 21 adapted to move and hold the contact spring 22 a suitable distance away from contact spring 23 while said prop lever is in a certain position. 20

25 A curved projection from prop lever 19 extends into the path of the pin 18 and said projection is so located that at a suitable time after the last tooth of the wheel 11 has disengaged the lever 12, the pin 18 will engage said projection and quickly operate the lever 19 to move spring 22 out of contact with spring 23. Said projection from lever 19 is of such form that it will thereafter hold said spring 22 out of contact with 30 spring 23 until just prior to the engagement of the first of the teeth of the wheel 11 with the projection on the signaling lever 12, and so that when said pin 18 disengages said projection from the lever 19 it 35 will permit said lever 19 to instantaneously move to the position in which it permits spring 22 to make contact with spring 23. The non-interference electromagnet 24 has an armature structure 25 pivoted at 26 and having its left hand end extending into the path of arm 20 of the prop lever 19. When the prop lever 19 moves in the direction whereby it will permit spring 22 to move toward spring 23, the lower end of said arm 20 is 40 brought into engagement with the armature structure 25 to hold said armature structure in attracted position. 45

An arm 27 extends from the armature structure so that when the armature structure is in retracted position, this arm engages pallet lever 28 and thereby stops the train, and the relation of said arm 27 to the pallet lever 28 must be such that when the lever 19 is moved by pin 18 to separate 50 spring 22 from spring 23, arm 27 will not engage lever 28 until after the separation of said springs. The free end of contact spring 30 lies in the path of insulating pin 29 carried by the sector gear 9. The contact spring 31 is so mounted that its free

end is normally not in contact with the spring 30, but when the sector 9 is started downwardly upon winding of the spring, the pin 29 allows spring 30 to make contact with spring 31. 55

Referring again to Fig. 1, current normally flows from the source 3 through wire 32 to contact 15 at station A and serially upward through similar contact 15 at all the other stations, thence through resistance magnet 4 to wire 33 and serially downward through contact 23 at each station, to and through wire 34 and serially upward through contact 22, non-interference magnet 24 and contact 30 at each station, to and through wire 35 and serially downward through contacts 31 and 17 at each station, thence upward through wire 36 to and through wire 37 and serially downward through the signal receiving devices 1 and 2 at each station, to and through wire 38 and serially upward through contact 14 at each station, to and through resistance magnet 5, to and through wire 39 and serially downward through contact 16 at each station to the other side of source 3. The winding of the non-interference magnets 24 and the resistance magnets 4 and 5 is such that they will be sufficiently energized to draw their armatures into attracted position when energized by a current which is insufficient to cause magnet 1 and the magnets provided in the devices 2 to actuate their armatures, the resistance of said magnets 4, 5, and 24 being such that the volume of current which the source 3 can send through said magnets and the path already described will not only be insufficient to operate the signaling devices connected in the wire 37, but will be so small as to use a minimum amount of energy for maintaining the constant test and securing non-interference between the various signaling stations. As the armature of both magnets 4 and 5 are normally attracted, the circuit of alarm 6 is open and the alarm does not sound. If the main circuit should be interrupted or the main source 3 should fail, the armatures of magnets 4 and 5 will be retracted to close the circuit of alarm 6. It will thus be seen that whenever the current flow in such main circuit is insufficient, the fact will be announced by alarm 6. 95

It will be noticed that each contact spring is provided with two terminals and the wires to these contact springs are separately attached, one to each terminal. By thus making the material of the contact spring itself an essential part of the normal closed circuit, it is impossible to have a loose contact at any terminal without indicating the same through failure of magnets 4 and 5. 100

It will be seen that such crosses in my system as might be most likely to occur will be indicated through the short circuiting of the 105 110 115 120 125 130

magnets 4 or 5 and the consequent operation of the alarm 6, and if deemed needful, low resistance relays (not shown) may, however, be placed in the circuit between wires 5 33 and 34, 34 and 35, and 36 and 37, controlling an alarm 6 or its equivalent, and the occurrence of any cross would be thereby indicated.

For the purpose of transmitting a signal 10 to the devices included in wire 37, the contact springs 14, 15, 16 and 17 are connected respectively in wires 38, 32, 39 and 35, and for the purpose of non-interference and succession the contact springs 22, 23, 30 and 31 15 are connected respectively in wires 34, 33, 34 and 35, the different groups of springs being controlled by the signaling mechanism, as already explained.

While I have shown the non-interference 20 magnet 24 as connected between contact spring 30 and contact spring 22 in the wire 34, the effectiveness of my system would not be altered if this magnet was included in the wire 34 below contact spring 22 as the shunting of the magnet 24 which would result from the operation of the contact springs 22 and 23 associated therewith would occur only during the time when its associated armature structure 30 would be locked in attracted position.

The operation of the portion of my invention provided for the purpose of securing non-interference is as follows: In the event that the lever 8 of the box located at station 3 B inclosed by the dash line in Fig. 1 is pulled, the first movement of pin 29 away from spring 30 allows this spring to make contact with spring 31. This short-circuits all the non-interference magnets 24 of boxes 40 which are located above the box pulled. The armature structures 25 of such magnets now retract and their arms 27 are moved into the path of their co-operating pallet levers 28, and thereby prevent running of their associated trains in the event of any of such boxes being pulled.

Upon release of the sector, pin 18 rotates with the signal wheel in a counter-clockwise direction for a suitable test period, the duration of which is measured by the distance the signal wheel 11 must move before the pin 18 is withdrawn from supporting the left hand end of the lever 19. When the pin 18 is thus withdrawn the lever 19 falls 55 and allows spring 22 to make contact with spring 23, thus deenergizing the non-interference magnets 24 of all boxes located below the box pulled. The duration of this test period must be at least double the time 60 interval which must elapse from the shunting of any group of non-interference magnets 24 until the arms 27 of all boxes whose magnets are so shunted are brought into the path of their co-operating pallet levers 28. 65 The reason this test period should be greater

than the interval determined by the lag of the magnet and its associated parts is to prevent interference between, or loss of, signals in the event of a box being pulled at a time when a higher box has been running for so great a portion of its test period that the deenergizing of its magnet 24 will not result in its co-operating arm 27 being brought in the path of the lever 28 prior to the pin 18 being withdrawn from supporting lever 19.

Since it requires an appreciable lapse of time after the closing of any set of contact springs 30 and 31 for the arms 27 associated with the magnets 24 shunted by the closing of such springs to be brought within the path of their respective co-operating levers 28, the test period of every box must be at least of such length that if at the time such box is pulled a higher box has already run for such time that the remaining portion of its test period is less than such appreciable lapse of time, the test period of such lower box must be of such duration as to extend for said appreciable lapse of time after its magnet 24 has been shunted by the contacting of springs 22 and 23 in the upper box at the conclusion of the test period of such upper box.

To allow for possible variations in the running of the signaling mechanisms of the various boxes, the test period just described should be further lengthened, as will be well understood by those skilled in this art.

It will thus be seen that just prior to the commencement of the transmission of the signal resulting from the engagement of the teeth of any wheel 11 with its associated lever 12, the armature structure of the associated non-interference magnet 24 will be 100 locked in its attracted position and will remain so locked until after the last of the teeth of the wheel 11 has engaged the lever 12 so that, after any box has commenced the transmission of any round of its signal, the 105 operation of such box cannot be interrupted through the action of its non-interference mechanism. It will further be seen that upon the completion of the transmission of each round of the signal of any one of these 110 boxes, its pin 18 will move the lever 19 to separate spring 22 from spring 23 and to further move said lever 19 far enough away from armature structure 25 so that if the magnet 24 is not energized, due to the pulling of any box located below and the consequent closing of springs 30 and 31 associated therewith, the arm 27 will be moved into the path of the lever 28 and thus stop the rotation of its associated signal wheel 115 until such time as magnet 24 is again energized.

The operation of the portion of my invention provided for the purpose of securing successive action of a plurality of boxes 120

pulled at or about the same time, is as follows:—In the event that the box located at station A was pulled and subsequent to the pulling of said box and before said box came to rest, the boxes at stations B and C were pulled, the first movement of the pin 29 of the box at station A would permit its associated spring 30 to move into contact with its spring 31 and thereby shunt the non-interference magnets 24 of the boxes at stations B and C through the following path: from the spring 30 in box A to wire 34 and therein through spring 22, magnet 24, and spring 30 of boxes B and C, to wire 35 and therein through springs 31 and 17 of boxes C and B to spring 31 in box A, which is in contact with spring 30 therein. The result of thus short-circuiting the non-interference magnets of the boxes at stations B and C will be to permit their armature structures 25—27 to move into retracted position and thereby prevent the running of these boxes. After the conclusion of the intended number of rotations of the signal wheel 11 of the box at station A, the pin 29 associated therewith will move the contact spring 30 away from the associated contact spring 31, thereby opening the short circuit hereinbefore described. The opening of the short circuit between the springs 30 and 31 of the box at station A will not cause the energization of the magnet 24 of the box at station C owing to the shunting of said magnet by the similar action of springs 30 and 31 in the box at station B when that box was pulled. However, the opening of this short circuit at station A would result in the energization of the magnet 24 in the box at station B and thereupon said box would proceed to run until its signal wheel had been rotated the intended number of times, when the pin 29 associated with the box at station B would move its contact spring 30 away from the associated contact spring 31, thereby opening the short circuit of magnet 24 of the box at station C. From the foregoing it will be seen that if two or more boxes are simultaneously pulled, the box at the lowest location will immediately shunt the magnets 24 of the higher boxes which will thereby be prevented from running until the lowest box has completed its intended run. It will further be seen that when the magnets 24 of two or more boxes have been shunted by the pulling of a lower box, and the boxes having such shunted magnets have been pulled, after the conclusion of the intended run of the lower box, the shunt will be removed from the magnet 24 of the lowest waiting box, allowing this box to run, but the other box or boxes will be prevented from running until this second box has completed its intended run, when the remaining boxes will be successively released in like order.

65 In the event that the box located at station C was pulled and at a time subsequent to the pulling of said box when the withdrawal of its pin 18 from supporting its lever 19 will prevent the retraction of its armature structure 25, the boxes at stations A and B were pulled, the rotation of the wheel 11 of the box at station C would not be affected by the shunting of its magnet 24 incident to the pulling of the boxes at said stations A and B until after the last of the teeth on said wheel 11 has passed out of engagement with the signaling lever 12 associated therewith. When, however, the lever 19 associated with the box at station C so moved to hold its associated armature structure 25 in attracted position, it also permitted its spring 22 to move into contact with its spring 23 and thereby shunted the magnets 24 of the boxes at stations A and B through the following path: from spring 23 in the box at station C to wire 33 and therein through springs 23 at stations B and A, to wire 34 and therein through springs 22, magnets 24, and springs 30 at stations A and B to spring 22 at station C which is in contact with spring 23 therein. The result of thus short-circuiting the non-interference magnets of the boxes at stations B and A will be to permit their armature structures 25—27 to move into retracted position and thereby prevent the running of these boxes. After the last of the teeth of the wheel 11 of the box at station C has passed out of engagement with its associated signaling lever 12, the pin 18 moving with said wheel will raise the lever 19 and thereby move spring 22 away from the associated contact spring 23, thereby opening the short circuit hereinbefore described. Inasmuch as the magnet 24 of the box at station C was shunted when the boxes at stations A and B were pulled, through the action of their spring 30 and 31, the armature structure 25 at said station C is permitted to retract upon the lifting of the lever 19 just described and in so retracting will move its arm 27 in the path of its lever 28 and thereby stop the running of the box at station C. The opening of the short circuit between the springs 22 and 23 at station C will not cause the energization of the magnet 24 at station B, owing to the shunting of said magnet by the springs 30 and 31 in the box at station A when that box was pulled. However, the opening of this short circuit at station C would result in the energization of the magnet 24 in the box at station A and thereupon said box would proceed to run until its signal wheel had been rotated the intended number of times, when the box at station B would be permitted to run through the operation already described. When the wheel 11 at station B has been rotated its intended number of times, the shunt around the magnet 24 at station C would be likewise removed, where-

upon the running of said box would be resumed. From the foregoing it will be seen that if the first tooth of the wheel 11 of any box has engaged the signaling lever 12 associated therewith, the pulling of any box or boxes located below such running box will not cause the running of said upper box to be interrupted until after the last of the teeth of its wheel 11 has disengaged its signaling lever 12. It will further be seen that under these circumstances the running of such lower boxes will be restrained until after the last of the teeth of the wheel 11 of the upper box has disengaged the associated signaling lever 12, whereupon said restrained boxes will follow in succession, the box at lowest location always taking precedence as already described. Thus, the operation of the portion of my invention provided for the purpose of securing non-interference and succession is such that the signal from the lowest point of fire danger is given the right of way, with a minimum delay, and there can be no confusion of signals. For example, a fire might start on a lower floor of a building, the smoke going through some vertical opening to an upper floor and there making itself known. If a box on the upper floor was first operated, the box on the lower floor, when operated, would detain the upper box at the end of the current round and immediately transmit its own signal.

The operation of the portion of my invention provided for the purpose of causing the actuation of the signal receiving devices included in the wire 37 is as follows: During the rotation of signal wheel 11, the teeth thereof are successively brought into engagement with signaling lever 42. The operation of this lever causes the closing and opening of contact springs 14, 15 and 16, 17. When these contacts are closed current may flow from source 3 through wire 32 to spring 15 in the operating box, where it divides into three branches, as follows:-(1) from spring 15 through spring 14, downward in wire 38, upward in wire 37 through signal receiving devices 2 and 1, downward in wire 36, upward in wire 35 to spring 17 in the operating box to spring 16 therein; (2) from spring 15 in the operating box, upward through wire 32, through magnet 4, downward in wire 33 to spring 23 in the operating box, spring 22, magnet 24, spring 30, spring 31, and spring 17 to spring 16 therein; and (3) from spring 15 in the operating box through spring 14, upward in wire 38, through magnet 5, downward in wire 39 to spring 16 in the operating box—here the three branches join and the current returns to source 3 downward through wire 39. On account of the great diminution of the resistance of the path including the signal receiving devices 1 and 2, the current passing

through said devices will be greatly increased and will constitute the major portion of the total flow from source 3, the restraining effect of resistance magnets 4 and 5 being sufficient to reduce the leakage ⁷⁰ around said signaling devices 1 and 2 to an insignificant amount.

It will be noted that the test current normally flows through the wire 37 in the opposite direction to the signaling current ⁷⁵ which flows through said wire while the springs 14, 15 and 16, 17 are in contact, which has a very beneficial effect in that it tends to overcome and neutralize any residual magnetism in the magnet 1 and in the devices 2. In practice, this results in much more accurate operation of all signaling devices used in this circuit. An important advantage obtained through the use of this arrangement is that an accidental interruption ²⁰ of the circuit will not cause the signal receiving devices 1 and 2 to act, thus avoiding unnecessary confusion and disturbance, while at the same time, such breaking of the circuit will affect magnets 4 and 5, thus indicating ²⁵ at the alarm 6 a disturbance to the circuit.

The action of the contact springs 14, 15 and 16, 17 will only vary the current in the magnets 4 and 5, but not at any time interrupt or reverse the direction of said current through these magnets, and signals can, therefore, be transmitted by means of these contact springs without affecting the alarm 6. ⁹⁵

While I have chosen to refer to the various signaling stations as being located at varying altitudes, I have only done so with the idea of securing clearness of description, but it will be obvious to those skilled in the art that the physical location of the various ¹⁰⁰ signaling stations is of no consequence but that the desired sequence of operation is obtained by the order in which the mechanisms of the various stations are electrically connected. For like purposes of clearness I ¹⁰⁵ have shown and described the magnets 4 and 5 as having sufficient resistance to produce the required results, but these magnets may be of much lower resistance and a suitable separate resistance serially connected therewith, and many other similar changes may be made in the construction and arrangement of my invention without departing from the spirit thereof. ¹¹⁰

While I consider it desirable to provide ¹¹⁵ relays for controlling the alarm 6, if it is deemed unnecessary to provide two relays, a suitable resistance may be substituted for either the resistance magnet 4 or the resistance magnet 5 and the remaining relay will ¹²⁰ give an effective test of the continuity of the entire circuit, and if desired both relays may be dispensed with and suitable resistances substituted for the magnets thereof and under these circumstances the condition of ¹²⁵ ¹³⁰

the circuit may, if desired, be determined or indicated by a suitable measuring or current detecting instrument included at any convenient point in said circuit, or by using the armature of the non-interference magnet as an indicator or to operate any well known indicating mechanism suitable therefor.

The signal station mechanism shown in Fig. 2 is provided for the purpose of more clearly disclosing the operative relations of the various instrumentalities shown diagrammatically in Fig. 1, but any signaling mechanism arranged to suitably operate similar instrumentalities may be used in place thereof, and such mechanism does not form part of my present invention.

What I claim is:—

1. The combination of a circuit including a source of current and a plurality of signal transmitting devices, non-interference magnets therefor included in said circuit, one or more signal receiving devices so connected in said circuit as to be responsive to all signals of said transmitting devices, and means for operatively altering the condition of the non-interference magnets of a plurality of said signal transmitting devices without operatively affecting the signal receiving devices.
2. The combination of a circuit including a source of current and a plurality of signal transmitting devices and non-interference magnets therefor included in said circuit, one or more signal receiving devices so connected in said circuit as to be responsive to all signals of said transmitting devices, and means for short-circuiting the non-interference magnets of a plurality of said signal transmitting devices without operatively affecting the signal receiving devices.
3. The combination of a circuit including a source of current and one or more signal receiving devices, with a plurality of signal transmitting devices and non-interference magnets therefor included in said circuit, means controlled and operated by each transmitting device for short-circuiting the non-interference magnets of other transmitting devices, and means controlled and operated by each transmitting device for reversing the current through said receiving devices.
4. The combination of a circuit including a source of current, one or more signal receiving devices, and two resistances normally in series therewith, with a plurality of signal transmitting devices, non-interference magnets therefor, means controlled by each transmitting device for short-circuiting the non-interference magnets of other transmitting devices, and means controlled by each transmitting device for connecting said resistances in multiple with each other and with said receiving devices.
5. The combination of a circuit including

a source of current, one or more signal receiving devices, and two resistances normally in series therewith, with a plurality of signal transmitting devices, non-interference magnets therefor, means controlled by each transmitting device for short-circuiting the non-interference magnets of other transmitting devices, means controlled by each transmitting device for connecting said resistances in multiple with each other and with said receiving devices, and means controlled by each transmitting device for reversing the current through said receiving devices.

6. The combination of a circuit including a source of current and one or more signal receiving devices, with a plurality of signal transmitting devices, non-interference magnets therefor, means associated with each transmitting device for short-circuiting certain non-interference magnets without operatively affecting the signal receiving devices and means associated with each transmitting device for subsequently short-circuiting other non-interference magnets.

7. The combination of a circuit including a source of current and one or more signal receiving devices, with a plurality of multiple-round signal transmitting devices, non-interference magnets therefor, means for operatively altering the condition of certain non-interference magnets during the entire signal, and means for operatively altering the condition of other non-interference magnets during each round of the signal.

8. The combination of a circuit including a source of current and one or more signal receiving devices, with a plurality of multiple-round signal transmitting devices, non-interference magnets therefor, means for short-circuiting certain non-interference magnets during the entire signal, and means for short-circuiting other non-interference magnets during each round of the signal.

9. The combination of a circuit including a source of current and one or more signal receiving devices, with a plurality of multiple-round signal transmitting devices, non-interference magnets therefor, means associated with each transmitting device for short-circuiting certain non-interference magnets during the entire signal, and means associated with each transmitting device for short-circuiting other non-interference magnets during each round of the signal.

10. The combination of a circuit including a source of current and one or more signal receiving devices, with a plurality of multiple-round signal transmitting devices, non-interference magnets therefor, means controlled by each transmitting device for short-circuiting certain non-interference magnets during the entire signal, and means controlled by each transmitting device for short-circuiting other non-interference magnets during each round of the signal.

11. The combination of a circuit including a source of current and one or more signal receiving devices, with a plurality of signal transmitting devices, non-interference magnets therefor, means controlled by each transmitting device for short-circuiting certain non-interference magnets, means controlled by each transmitting device for subsequently short-circuiting other non-interference magnets, and means controlled by each transmitting device for reversing the current through said receiving devices.

12. The combination of a circuit including a source of current, one or more signal receiving devices, and two resistances normally in series therewith, with a plurality of signal transmitting devices, non-interference magnets therefor, means controlled by each transmitting device for short-circuiting certain non-interference magnets, means controlled by each transmitting device for subsequently short-circuiting other non-interference magnets, and means controlled by each transmitting device for connecting said resistances in multiple with each other and with said receiving devices.

13. The combination of a circuit including a source of current, one or more signal receiving devices, and two resistances normally in series therewith, with a plurality of signal transmitting devices, non-interference magnets therefor, means controlled by each transmitting device for short-circuiting certain non-interference magnets, means controlled by each transmitting device for subsequently short-circuiting other non-interference magnets, means controlled by each transmitting device for connecting said resistances in multiple with each other and with said receiving devices, and means controlled by each transmitting device for reversing the current through said receiving devices.

14. In a signaling system having a signaling circuit, a plurality of signal transmitting devices each having a non-interference magnet, a loop of the signaling circuit including all of said magnets, and means operated by each of said transmitting devices for cross-connecting a portion of said loop including the magnets of a plurality of other transmitting devices.

15. In a signaling system, the combination with a plurality of signal transmitting devices and non-interference magnets therefor, of a conductor serially including said magnets, a second conductor connected to one end of the first conductor and extending past said magnets, and means associated with each transmitting device for cross-connecting said conductors.

16. In a signaling system, the combination with a plurality of signal transmitting devices and non-interference magnets there-

for, of a conductor serially including said magnets, a second conductor connected to one end of the first conductor and extending past said magnets, and means controlled by each transmitting device for cross-connecting said conductors.

17. In a signaling circuit, the combination with a plurality of signal transmitting devices, non-interference magnets therefor, and a signal receiving device, of a conductor serially including said magnets, a second conductor connected to one end of the first conductor and extending past said magnets, means controlled by each transmitting device for cross-connecting said conductors, and means controlled by each transmitting device for reversing the current only through the portion of said circuit including said receiving device.

18. In a signaling system, the combination of a circuit including a source of current, a signal receiving device, two resistances normally in series therewith, a plurality of signal transmitting devices, and non-interference magnets therefor, with a conductor serially including said magnets, a second conductor connected to one end of the first conductor and extending past said magnets, means controlled by each transmitting device for cross-connecting said conductors, and means controlled by each transmitting device for connecting said resistances in multiple with each other and with said receiving device.

19. In a signaling circuit, the combination with a plurality of signal transmitting devices and non-interference magnets therefor, of a conductor serially including said magnets, a second conductor connected to one end of the first conductor and extending past said magnets, a third conductor connected to the other end of the first conductor and also extending past said magnets, and means for cross-connecting said conductors.

20. In a signaling circuit, the combination with a plurality of signal transmitting devices and non-interference magnets therefor, of a conductor serially including said magnets, a second conductor connected to one end of the first conductor and extending past said magnets, a third conductor connected to the other end of the first conductor and also extending past said magnets, and means associated with each transmitting device for cross-connecting said conductors.

21. In a signaling circuit, the combination with a plurality of signal transmitting devices and non-interference magnets therefor, of a conductor serially including said magnets, a second conductor connected to one end of the first conductor and extending past said magnets, a third conductor connected to the other end of the first conductor and also extending past said magnets,

- and means controlled by each transmitting device for cross-connecting said conductors.
22. In a signaling circuit, the combination with a plurality of signal transmitting devices, non-interference magnets therefor, and a signal receiving device, of a conductor serially including said magnets, a second conductor connected to one end of the first conductor and extending past said magnets, a third conductor connected to the other end of the first conductor and also extending past said magnets, means controlled by each transmitting device for cross-connecting said conductors, and means controlled by each transmitting device for reversing the current only through the portion of said circuit including said receiving device.
23. In a signaling system, the combination of a circuit including a source of current, a signal receiving device, two resistances normally in series therewith, a plurality of signal transmitting devices, and non-interference magnets therefor, with a conductor serially including said magnets, a second conductor connected to one end of the first conductor and extending past said magnets, a third conductor connected to the other end of the first conductor and also extending past said magnets, means controlled by each transmitting device for cross-connecting said conductors, and means controlled by each transmitting device for connecting said resistances in multiple with each other and with said receiving device.
24. A plurality of signaling stations, signal transmitting mechanism at each station, setting mechanism associated with each transmitting mechanism adapted to adjust said mechanism for the transmission of a signal therefrom, electro-magnetic controlling mechanism at each station adapted to prevent the transmission of a signal from that station under certain circuit conditions, means associated with and controlled by the running of each signal transmitting mechanism for preventing its associated controlling means from acting between the commencement and completion of any round of its signal, circuit changing mechanism associated with each setting mechanism and operated thereby, and suitable circuit connections between the signaling stations so connected with said circuit changing mecha-

nism and said electro-magnetic controlling mechanism that the operation of any setting mechanism will adjust said circuit connections so that the electro-magnetic controlling mechanism of other stations will be subjected to circuit conditions adapted to prevent the transmission of signals therefrom without so adjusting the circuit connections for the electro-magnetic controlling mechanism of all stations.

25. A plurality of signal transmitting stations, non-interference mechanism associated with each station, means for setting each station for the transmission of a signal, two circuit changing mechanisms associated with each transmitting station, one of which is operated by said setting means and the other of which is maintained in operated condition between the commencement and completion of each round of the signal of its station, means associated with and controlled by each signal transmitting station for preventing its associated electro-magnetic controlling mechanism from acting between the commencement and completion of any round of its signal, and suitable circuit connections between the stations so connected with said circuit changing mechanisms and said electro-magnetic controlling mechanism that the operation of one of the circuit changing mechanisms of any station by its associated setting means will so adjust said circuit connections that the electro-magnetic controlling mechanism of certain stations will be subjected to circuit conditions adapted to prevent the transmission of signals therefrom, said circuit connections being further so arranged that the other circuit changing mechanism of such station when in operated condition will so adjust said circuit connections that the electro-magnetic controlling mechanism of other stations will be subjected to circuit conditions adapted to prevent the transmission of signals therefrom.

In witness whereof, I hereunto subscribe my name, this 22nd day of December, A. D., 1918.

CLARENCE E. BEACH.

Witnesses:

C. M. CONNERTON,
A. L. PECK.
